United States Patent Office.

GEORGE SHATSWELL, OF WAUKEGAN, ILLINOIS.

Letters Patent No. 96,976, dated November 16, 1869.

IMPROVED RAILWAY-CAR COUPLING.

The Schedule referred to in these Letters Patent and making part of the same.

To all whom it may concern:

Be it known that I, GEORGE SHATSWELL, of Waukegan, in the county of Lake, and State of Illinois, have invented an Improved Car-Coupling; and I do hereby declare that the following is a full and exact description thereof, which will enable those skilled in the art to make and use the same, reference being had to the accompanying drawings, and letters marked thereon, making a part of this description, in which—

Figure 1 is a perspective representation of my invention.

Figure 2, a longitudinal central section of the same. The present invention relates to an improvement in that class of couplings which is designed to couple railroad-cars automatically; and

Its nature consists in the novel construction of a sliding and swinging catch, so arranged that the weight of the link, when it is entering the bumper, will bring the catch into place, in combination with a spring for holding the catch up after it has been raised up to uncouple the cars, as the whole is hereinafter fully described.

A represents that part of a bumper which is placed under the platform of a car, and which is so slotted out at T, fig. 1; as to receive a catch, Z.

This catch is provided with a slot, P, fig. 2, running transversely through it, to receive a pin, K, which holds the catch to the bumper A, and allows it to have a reciprocating movement, longitudinally, with a coupling-bar, C, in order that the end J may slide under, and move out from a rib or bar, G, cast or welded solid to the bumper A, as shown in both figures, this arrangement being such that the catch cannot accidentally get out of place when the cars are moving upon the track; and if greater strength and security are required, a pin, W, fig. 1, may be put through holes I X F, fig. 2.

This catch is also provided with a shoulder, J', fig. 2, which locks over the spear-headed ends D of a coupling-bar, C, and with a vertical mortise or slot, N, to allow a spring, L, fastened to bumper A, to pass into, when the catch is raised up, as shown at fig. 2, the spring resting on the corner m, which defines one end of the mortise, holds the catch in position until the weight of the bar brings it down.

To accomplish this latter movement, a strong curved plate, M, is rigidly fastened to the under side of the catch Z, and its lower end, b, is so bent down as to allow a head, D, of bar C readily to pass on to the bent part M, and by its weight bring the catch down, as shown at fig. 1.

A lug, E, projecting down from the central part of the under side of the bar C, and striking against the end H of bumper A, prevents the head D from going in so far as to break or disarrange said catch.

The part B represents a portion of the end of a car, and S is a rope or chain, by means of which the catch Z is raised up to uncouple the cars. Any device, such as a lever, may, however, be used instead of the rope S.

Having thus described my invention, What I claim, and desire to secure by Letters Patent of the United States, is—

The catch Z, arranged to have a sliding and swinging movement in the bumper A, and provided with a curved plate, M b, in combination with the spring L, rope S, and coupling-bars C D D, the latter being provided with a lug, E, as set forth.

GEORGE SHATSWELL.
